UNITED STATES PATENT OFFICE

ALFRED LOMNITZ, OF BERLIN-CHARLOTTENBURG, GERMANY

DISPLAY DEVICE

Application filed October 20, 1931, Serial No. 569,991, and in Germany May 23, 1931.

The invention makes use of the known idea of calling attention to articles of all kinds which are offered for sale by displaying the articles in movement in the shop window.

For this purpose the invention employs the known means such as rotating tables, rotating plates and chain conveyors.

The subject of the invention is a combination of these different possibilities of movement, in which in a rotating table one or more chain conveyors rotating with the table are built in, so that the articles moved by these chain conveyors execute a vertical motion and a circular motion simultaneously. If desired, separate rotating plates may be arranged in the main rotating table in the spaces between the chain conveyors. The new effect is then obtained that all the articles shown in the shop window are in motion, the drive for all parts is concealed by means of traps or screens. Central or individual drives may be employed.

A method of carrying out the invention is illustrated by way of example in the accompanying drawings.

Fig. 1 shows a practical general view of the new device for displaying goods,

Fig. 2 shows diagrammatically the driving arrangement as seen from above,

Fig. 3 is a side elevation of the same arrangement,

Figs. 4 and 5 are two details.

In the foundation casing *a* of any desired shape is mounted the rotating table *b* of suitable diameter, for example, the diameter which can be employed in an ordinary shop window. Covered by screens *c*, chain conveyors *e* and *f* pass through the table *b*. These must also rotate with the table *b* independently of their own motion. The chain conveyors have single or double sided carrying surfaces *g* or the like, on which the goods to be shown or displayed are placed.

When the carrying surfaces *g* for the goods to be shown are made only one sided so that as they move they always display the same goods its change may easily be effected by replacing the goods at the side turned away from the shop window. The chain conveyor

may also be carried either so high through the ceiling or so far below the floor that it is there possible to replace the articles displayed. Fig. 5 shows such an arrangement. Here *D* is the ceiling and *F* the floor through which pass the chain conveyors *e* and *f*. In general, the carrying surfaces *g* are constructed in two parts so that they can always take two displayed articles of which one is seen from each side of the device. In this way the attraction of the shop window is especially great.

The motion arrangement for the chain conveyors *e*, *f* may be as desired. They may move in the same direction or in opposite directions up and down. The one is then shorter than the other above the table *b* so that they can cross. How far they are carried down below the table *b* is determined from considerations of space and utility. The spaces left free by the screens *c* may in any desired manner be fitted, for example, with smaller rotating plates *h*.

The drive of the various parts, namely, the chain conveyors *e* and *f* and the rotating plates *h*, may be effected in any desired manner. The central drive may be employed from which, by means of shafts and gear wheels, the separate driving shafts of the parts are driven. Under certain circumstances it is, however, of advantage, at least in the chain conveyor, to employ separate drives since then there is the possibility of varying the relative motions between the individual parts.

The central drive is illustrated in Figs. 2 and 3. Here for driving the rotating table *b*, use is made, for example, of an electric motor *i* which transmits through toothed wheel and worm *k* to toothed wheels *l* by which the shaft *m* is driven. This drives through bevel wheels *n* a shaft *o*, from which also through bevel wheels *p* a shaft *t* is driven, on the ends of which are provided driving wheels, for example, toothed wheels *s* for the chains *v* of the chain conveyor *e*. In this way the chain conveyor *e* is driven which for the rest is guided over rollers *x*. The chains *z* of the chain conveyor *f* which is at right angles to *e*, are driven directly from the shaft *m* by

means of toothed wheels, chain wheels y and the like, there provided. In the chains v and z are suspended so as to be freely rotatable single or double sided plates g on which are placed the goods to be displayed. The method of connecting is, for example, shown in Fig. 4 where z' indicates the chain of the chain conveyor. The horizontal circular movement of the rotating table b which rests on three rollers r is produced by means of a chain wheel n' carried round by the chain z of the chain conveyor f , which is connected by a shaft w with one of these rollers r . The four rotating plates h are each provided below the table b with a pulley q , over which runs a common driving belt u (for example a spiral wire) with the object of simultaneous tightening.

This belt is driven by being guided over a pulley r^2 of the shaft w . The current required for driving the apparatus is supplied to the motor i through a sliding contact i' provided on the floor of the bearing.

In connection with the constructional form of the arrangement referred to, it is to be re-

marked that of course use may here be made of experience in this connection.

The description is to be completed by stating that the parts g may be utilized at the front and the back so that after the table has turned through 180° , other articles appear in the chain conveyor.

What I claim is:

1. Apparatus for displaying goods comprising a rotatable table, a plurality of smaller tables rotatably mounted thereon, means for causing the smaller tables to rotate relatively to the larger table, a plurality of chain conveyors adapted to carry goods for display purposes mounted on and rotatable with the larger table, the direction of travel being substantially parallel to the axis of rotation of the table, and means for driving the chain conveyors.

2. Apparatus as claimed in claim 1 having chain conveyors arranged in intersecting planes.

In testimony whereof I have signed my name to this specification.
